TALKING TOY MECHANISM

Filed March 21, 1923

FIG. 2

INVENTOR.

FRED EVANS

BY

Charles J. Wilson.

ATTORNEY.

UNITED STATES PATENT OFFICE.

FRED EVANS, OF SUMMIT, NEW JERSEY, ASSIGNOR, BY MESNE ASSIGNMENTS, TO
VOICES INCORPORATED, A CORPORATION OF DELAWARE.

TALKING-TOY MECHANISM.

Application filed March 21, 1923. Serial No. 626,501.

This invention relates to sound-producing devices such as are used in connection with talking toys, more particularly talking dolls. Specifically, this device is intended and designed for use in connection with a doll, the position of which may be changed, this movement causing the doll to emit a sound such as "ma-ma".

The main object of the invention is to provide a talking toy mechanism which is not only simple and efficient in operation and construction, but also one which is not likely to get out of order and is compact and easily inserted in toys.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings, where in I have shown a preferred form of embodiment of my invention:

Figure 1 is a view of the device in side elevation, the sound producing elements being shown in cross-section.

Figure 2 is a bottom plan view of the device.

With reference now to the drawings in which similar reference characters refer to similar parts throughout the views thereof, reference character 1 designates a tubular casing, preferably cylindrical in form, and constructed of cardboard, fibre or other similar material.

Positioned in the casing 1, intermediate its ends, is a head 2 channelled as indicated at 3 whereby there may be attached thereto the marginal edge of a tubular bellows 4, the other end of this bellows being closed by a head or disc 5 indicated in dotted lines in Figure 1, this disc being preferably made of some heavy material such as lead so that it is weighted and will operate the bellows by gravity. It will be noted that the lower

marginal edge of the bellows overlies the channel formed in the head 2 and is held in this channel by means of a spring ring 6.

Attached to the weighted disc 5 and extending through the bellows and slidably through a suitable aperture formed in the head 2 is an operating rod or controlling member 7, the end of this rod projecting beyond the head 2 and having mounted thereon an operating cam 8. The construction of the device is such that when the parts are in the position shown in Figure 1, the weight 5 will have a tendency to collapse the bellows forcing the rod with its cam member away from the face of the head 2.

An aperture 9 is drilled through the head 2, and enclosing this aperture is a chamber 10 in which is mounted a reed 11, this reed being so positioned that as the bellows is collapsed and the air forced through the aperture 9, this expelled air will cause the reed to vibrate. Positioned also on the exterior surface of the head 2 is a chamber 12 provided with an orifice 13, this chamber 12 being mounted so as to overlie a portion of the chamber 10 and so positioned that the reed 11 extends thereinto.

The chamber 12, as is here shown, is semi-circular in cross-section, and a lip or valve 14 is mounted so as to over-lie the opening or orifice in the chamber 12, being secured thereto along the arcuate edge. The lip 14 is cut from a sheet of flexible, resilient material, and I have found that a good grade of sheet rubber will be most satisfactory for the purpose. The lip 14 has an extending portion 15 of the same material which extends beyond the straight edge of the chamber 12 and is so positioned as to lie in the path of the cam 8. The cam 8, as here shown, is preferably formed so as to have two projecting portions with a reentrant portion therebetween, this arrangement insuring that the cam will have a double action. The cam 8 is shown to be formed of a strip of light metal bent in the form explained and attached at either end to the rod 7. This construction of the cam, however,

is not necessary, but it will be clear that other constructions for the cam such as making it of wire bent in the proper form or of some other material will be equally satisfactory.

It will be seen that the head, 2, is positioned well away from either end of the casing, thereby providing an overlying portion of the casing which protects the sound producing and regulating parts. The casing is also provided at the opposite end with a head 16 indicated in dotted lines in Figure 1, this head, together with the mounting of the sound devices, providing that all the working parts will be well protected.

The operation of the device is as follows:

Assume that the doll has been moved to such a position that the parts occupy the relative locations indicated in Figure 1, the bellows now being full of air and the weight 5 at its farther limit of travel. As soon as the doll is moved to this position, the weight 5 will be moved by gravity so as to compress the air within the bellows, the bellows as shown being suitably creased so that it may easily fall into the collapsed position. As the weight travels downwardly, the air is expelled from the interior of the bellows through the orifice 9 into the reed chamber 10, through the reed into the orifice chamber 12. The expulsion of the air will cause the reed to vibrate and emit a sound, but the orifice 13 being closed by the lip, this sound will be muffled. However, as the weight 35 moves down, carrying the reed through therewith, the first hump on the cam will engage the lip at its projecting position and flex it away from the orifice 13 and open the orifice, whereupon the air compressed within 40 the bellows will escape quickly and cause the reed to vibrate rapidly, thereby emitting a clear note through the orifice. As the cam moves by the lip on the continued downward movement of the weight, the re-entrant 45 portion will next come opposite the projecting portion of the lip. This will permit the lip to flex backwardly to its normal position, closing the orifice 13 as shown at Figure 1. The action thereupon will be to muffle the sound of the reed, the two movements 50 of the lip away from and back so as to close the orifice 13, producing a distinct syllable.

The continued downward movement of the weighted reed and cam will, in turn, cause the second hump of the cam to engage the projecting portion of the lip, forcing it again away from the orifice 13 and permitting the reed to emit a second clear note. This action will continue until the second hump 60 rides off the lip, whereupon the orifice will be again closed.

When the body of the doll is moved to another position so as to reverse the position of the device, the weight will move by gravity away from the head 2 and thereby ex-

pand the bellows, whereupon the parts will be in condition for a second sound emission. On this movement of the weighty head of the tubular bellows the cam projection members on the control member 7 will easily slip by the projecting member on the valve 14 which they engage, by reason of the latter being formed of flexible rubber which will easily bend out of the way of the cam projections. On the backward movement of the weight so as to expand the bellows, air will enter the bellows, leaking in under the edges of the resilient lip in the reverse direction from the expelled air and also leaking in through the head 2 through the aperture in which the reed 7 projects. The parts being in the position shown in Figure 1, a second sound production may take place. While the cam here shown is such as to cause the emission of two distinct syllables, thereby giving the "ma-ma" sound, it will be clear that various other cam forms may be used, emitting syllables of different length, and also producing more than two syllables such as are now provided for.

It will be seen that I have provided a simple and effective device for sound production for use in the manner described, this device being very cheaply constructed and having no parts which are delicate and easily put out of order. The device is ruggedly constructed and will withstand rough usage such as dolls and toys are ordinarily subjected to. It will be seen that the sound may be easily regulated so as to provide for the production of sounds of varying qualities and characteristics, and by simple modifications in the cam form single syllables or a plurality thereof may be emitted, as desired.

As many changes could be made in this construction without departing from the scope of the following claims, it is intended that all matter contained in the above description or shown in the accompanying drawings shall be interpreted as illustrative only and not in a limiting sense.

Having thus described my invention, what I claim as new and desire to secure by Letters Patent is:

1. A device of the class described comprising in combination a casing, a head mounted therein, bellows attached to one face of said head, a weight mounted on said bellows, a rod attached to said weight and extending through said head, sound producing means mounted on the other face of said head in communication with the interior of said bellows, and means to control the characteristics of sound produced upon the expulsion of air from said bellows, said last named means including an orifice, a resilient lip covering said orifice, and a cam having a plurality of protuberances mounted on said rod to displace said lip from said orifice as said bellows is collapsed.

2. A device of the class described comprising in combination a casing, a head mounted therein, intermediate the ends thereof, a tubular bellows attached to one face of said head, a weight mounted on the other end of said bellows, a rod attached to the inner face of said weight and extending through said head, a reed chamber mounted on the other face of said head in communication with the interior of said bellows, an orifice chamber mounted on said head in communication with said reed chamber, a resilient closure mounted on said orifice chamber so as to cover said orifice, and a cam having a plurality of protuberances mounted on the end of said rod and so positioned as to displace said closure from said orifice as said rod moves through said head upon the collapse of said bellows.
3. A device of the class described comprising in combination a casing, a head mounted therein intermediate the ends thereof, the bellows attached to one face of said head, a weight closing the other end of said bellows, a rod attached to said weight projecting through said head, an aperture through said head, a reed chamber mounted on the other face of said head overlying said aperture, an orifice chamber on said head in connection with said reed chamber, a flexible, resilient closure for said orifice mounted on said orifice chamber and projecting beyond the walls thereof, a cam mounted on said rod beyond the face of said head and adapted to engage the extending portion of said closure, said cam being so formed as to cause said closure successively to open and close said orifice whereby to control the character of the sound emitted.
4. A device of the class described, comprising in combination, a casing, a head mounted in the casing, a bellows attached to one face of said head, a weight closing the other end of the said bellows, a rod attached to the said weight and passing movably through the said head, the said head having an aperture, a reed chamber and reed mounted externally on said head over the said aperture, a second chamber partly mounted upon the said head and partly upon the said reed chamber, the said reed forming the communicating passage for air between the two said chambers, the said second chamber having a flat bottom provided with an orifice, a resilient flap closure covering the said bottom and orifice externally and having a portion projecting beyond the said bottom and side of the chamber, and a cam having a plurality of rounded protuberances and mounted on the said rod and arranged to act upon the said projecting portion of the closure at intervals in passing the same as the bellows collapses and expands.
5. A device of the class described having in combination a collapsible air chamber, a sound reed operated thereby, means having an orifice through which the sound from the reed may escape, a valve normally closing said orifice and a control member, the control member having a member adapted to engage a member on the valve to open the valve when the air chamber is collapsed, and one of said members being formed of flexible rubber whereby the other member may easily slip by the same on one movement of the control member with respect to valve.
6. A device of the class described having in combination a collapsible air chamber, sound reed operated thereby, means having an orifice through which the sound from the reed may escape, a valve normally closing said orifice and a control member, the valve having a member of flexible rubber adapted to be engaged by the control member to open the valve when the air chamber is collapsed.
7. A device of the class described having in combination a tubular casing, a tubular bellows therein, one end of said bellows being weighted whereby the same may be operated by gravity, a sound reed carried by one end of the bellows and adapted to be operated thereby, means carried by said end of the bellows and having an orifice through which the sound from said reed may escape, a valve for opening and closing said orifice to control the sound therefrom, a control member passing through the bellows and through said head carrying said reed, said control member being slidably arranged with respect to said head, the control member having a member adapted to engage a member on the valve to open the valve when the bellows is collapsed, and one of said members being formed of flexible rubber.
8. A device of the class described having in combination a tubular casing, a tubular bellows therein, one end of said bellows being weighted whereby the same may be operated by gravity, a sound reed carried by one end of the bellows and adapted to be operated thereby, means carried by said end of the bellows and having an orifice through which the sound from said reed may escape, a valve for opening and closing said orifice to control the sound therefrom, a control member passing through the bellows and through said head carrying said reed, said control member being slidably arranged with respect to said head, and the valve having a member of flexible rubber adapted to be engaged by a plurality of projections on the control member to operate the valve.
9. A device of the class described having in combination a tubular casing, a tubular bellows therein, one end of said bellows being weighted whereby the same may be operated by gravity, a sound reed adapted to be operated by the bellows, means having an orifice through which the sound from the reed may escape, a valve for opening and

closing said orifice to control the sound therefrom, a control member attached to the weighted end of the bellows and passing through the bellows and into proximity to said valve, said control member having a member adapted to engage a member on the valve and one of said members being formed

of flexible rubber whereby the other member may easily slip by the same on one movement of the control member with respect to the valve. 10

In testimony whereof I affix my signature.

FRED EVANS.
